SPINNING RING AND TRAVELER THEREFOR

Harvey E. Herr, Buffalo, N. Y., assignor to Herr Manufacturing Company, Inc., Buffalo, N. Y., a corporation of New York

Application December 29, 1936, Serial No. 118,073

10 Claims. (Cl. 118—59)

This invention relates to certain new and useful improvements in the spinning rings and bar travelers employed in connection with spinning rings.

It has for one of its chief objects to so construct the spinning ring and bar traveler that an effective and extensive bearing contact is provided between these parts to assure a stable and uniform operation of the traveler and at the same time maintain the traveler in a constant position relative to the spool or bobbin to thereby afford an even and uniform thread-tension and reduce to a minimum the tendency of the thread to break.

Another object of the invention is the provision of a traveler which is so designed as to facilitate the threading operation without removing the traveler from the ring, as well as to so guide and direct the thread to and from the traveler as to eliminate its tail-whipping.

Other features of the invention reside in the construction and arrangement of parts herein-after described and particularly pointed out in the appended claims.

In the accompanying drawing:

Figure 1 is a fragmentary sectional side view of a spinning machine showing my traveler and ring applied thereto. Figure 2 is a top plan view of the spinning ring and bar traveler embodying my invention. Figure 3 is an enlarged cross section thereof taken on line 3—3, Figure 2. Figure 4 is an enlarged fragmentary cross section taken on line 4—4, Figure 2. Figure 5 is a perspective view of the bar traveler, showing the manner of engaging the thread therewith.

Similar characters of reference indicate corresponding parts throughout the several views.

In spinning machines of the character to which my invention is particularly applicable, the threads to be twisted are delivered by feed rolls (not shown) to a take-up spool 10 and traversing the same is a vertically-reciprocating bar 11, the spool extending through an opening 12 in the bar.

Mounted on the reciprocating bar 11 surrounding the take-up spool is a supporting member or holder 13 for the spinning or traverse ring 14 upon which the bar traveler, indicated generally by the numeral 15, is adapted to revolve. Rising from the base portion of the supporting member 13 is an inner annular guard flange or neck 16 which is spaced from the opposing inner edge of the spinning ring 14 to provide an annular channel 17 for receiving the depending legs of the bar traveler in the manner shown in Figure 4.

Preferably formed integrally with the supporting member 13, and rising therefrom in spaced concentric relation with the annular flange 16, is an outer annular flange 18 which is provided adjacent its lower end with an internal seat or shoulder 19. The spinning ring 14 is removably fitted within the outer flange 18 of the supporting member in spaced relation to the inner flange 16 thereof and has a depending attaching rim or flange 20 fitted snugly within the annular flange 18 and abutting at its lower edge on the seat 19 to support the spinning ring in a level or true running position. For the purpose of holding the spinning ring in its operative running position within the supporting member or holder 13, I provide a split-ring clamping member 21 which is adapted to be detachably fitted within the annular flange 18 for bearing contact with the top side of the spinning ring in the manner shown in Figures 3 and 4.

The spinning ring may be made of any suitable and well known material, being provided on its underside with an outwardly-inclined bearing face 22 for the bar traveler, while rising above its plane the ring has an annular wall or flange 23 which extends above the top edge of the guard flange 16 of the supporting member 13 and whose inner periphery constitutes a substantially upright bearing face 24 for the bar traveler. The inclined bearing face 22 of the ring is spaced above the opposing top side of the supporting member 13 and this space communicates with and forms a lateral continuation of the annular channel 17 for receiving the legs and bearing arms of the bar traveler.

The bar traveler 15 is constructed of steel wire and preferably shaped in the manner shown in Figures 2, 3 and 5, the same being bent substantially U-shaped to form a thread-engaging bar 25, legs 26 depending from the ends of the bar 25 and arranged to extend freely in the annular space or channel 17 formed between the neck 16 and the ring-bearing flange 23, and extensions or bearing arms 27 projecting outwardly through the lower end of the legs and adapted to enter the lateral continuation of the channel 17 into more or less hook-like engagement with the ring, the arms bearing against the bearing face 22 of the ring in the manner shown in Figure 4. By preference the cross bar of the traveler, as shown in Figures 2 and 5, is bent or deflected inwardly from its opposite ends into substantially the form of a wide V, so as to subtend an arc of the inner edge of the bearing ring 14, the resulting apex portion of the cross bar overhanging and extend-

ing inwardly of the upper edge of the guard ring 16 in its running or operating position, as depicted in Figures 2 and 4. At its apex the V-shaped cross bar terminates in an integrally formed thread-guiding loop which preferably depends therefrom into substantially inverted T-shaped form, and includes a neck portion 28 forming a continuation of the adjoining V-portions of the cross bar 25 and a lower enlarged portion 29 which extends uniformly on either side of the neck and whose wire parts or components are in the corresponding vertical planes intersecting the V-portions of the cross bar, as depicted in Figures 2 and 5. From the foregoing, it will be understood that the thread-guiding loop is formed from one length of wire with the bar traveler and produced by reverse bends consisting of companion inner bends 30, 30^a and outer bends 31, the latter and adjoining wire portions serving as guards to maintain the thread coupled with the traveler and accidentally preventing its displacement from the traveler. In threading the traveler, the thread from the take-up spool is guided around the bend 30^a, which is located at the far or trailing side of the traveler at one side of its apex, referring to Figure 2, and then spans the open neck 28 of the loop and thence is engaged with the companion bend 30 forwardly of the apex or center point of the traveler cross bar, as seen in Figure 5, from whence it leads to the take-off spool.

By this spinning ring and traveler structure, the ring affords an extensive bearing for the traveler when traveling at high speeds to assure its stable and uniform operation in a constant position relative to the take-up bobbin, and the traveler design itself insures the thread being coupled therewith both when in operation and when idle, and by its looped construction it can be conveniently threaded without removing the traveler from the ring.

I claim as my invention:

1. A device of the character described, comprising a supporting member containing a central opening through which a take-up spool is adapted to extend and having an annular flange rising therefrom about said opening, a spinning ring for a bar traveler mounted on said supporting member in spaced concentric relation about said flange, said ring including a bearing face on its underside and a substantially upright inner peripheral wall extending above the top of said flange and constituting a bearing face, and a bar traveler having a thread-engaging bar containing thread-loops disposed above the plane of the top edge of the annular flange and having depending legs at its ends terminating in bearing arms for engagement with the underside of the bearing face of the spinning ring, the traveler-legs being engageable at their outer sides with the peripheral bearing face of the inner wall of said ring and adapted to engage at their inner sides with said annular flange to support the traveler out of contact with the take-up spool.

2. A device of the character described, comprising a supporting member containing a central opening through which a take-up spool is adapted to extend and having an annular flange rising therefrom about said opening, a spinning ring for a bar traveler mounted on said supporting member in spaced concentric relation about said flange, said ring including a bearing face on its underside and an inner peripheral wall extending above the top of said flange, and constituting a substantially upright inner bearing face, and a bar traveler

having depending legs at its ends terminating in outwardly-directed bearing arms for engagement with the underside of the bearing face of said ring, the traveler legs being engageable substantially their full length with the inner bearing face of said ring and being adapted to engage said annular flange for holding the traveler out of contact with the take-up spool.

3. A device of the character described, comprising a supporting member containing a central opening through which a take-up spool is adapted to extend, a spinning ring for a bar traveler mounted on said supporting member, and an annular guard flange rising from the supporting member and extending part way into the spinning ring for holding the bar traveler out of contact with the take-up spool, said ring having its inner wall spaced concentrically relatively to said guard and extending upwardly beyond the same to provide a substantially upright bearing face for the legs of the traveler.

4. A bar traveler for a spinning ring, comprising a thread-engaging bar having depending legs terminating in bearing arms, said bar having a depending, substantially inverted T-shaped looped portion between its legs providing outwardly-opening thread-loops between said bar and the head portion of the T-shaped loop for guiding the thread.

5. A bar traveler for a spinning ring, comprising a thread-engaging bar having depending legs terminating in bearing arms, said bar having, substantially centrally thereof, an outwardly and inwardly bent looped portion formed integrally therewith below the plane of the bar to provide oppositely-facing thread guides at opposite sides of the center of the bar.

6. A bar traveler for a spinning ring, comprising a thread-engaging bar having depending legs terminating in bearing arms, said bar having a pair of endwise-facing thread-guiding loops between its ends and below the plane thereof, one of the loops guiding the thread from the take-up spool to the traveler and the other loop guiding the thread from the traveler to the take-up spool.

7. A bar traveler for a spinning ring, comprising a thread-engaging bar having depending legs terminating in bearing arms, said bar being bent laterally into substantially the shape of a V and provided at opposite sides of its resulting apex and below the plane of the bar with endwise-opening, thread-guiding loops.

8. A bar traveler for a spinning ring, comprising a thread-engaging bar having depending legs terminating in bearing arms, said bar being bent laterally into substantially the shape of a V and having a pendant loop at its apex formed integrally with the bar and composed of reverse bends, certain of such bends constituting thread guides.

9. A device of the character described, comprising a ring holder containing a neck through which a take-up spool is adapted to extend, a spinning ring for a bar traveler mounted on said holder in spaced concentric relation to its neck, and a bar traveler mounted on said ring to subtend an arcuate portion thereof and having a substantially V-shaped thread-engaging bar having its apex facing toward the ring-axis and provided with oppositely-facing thread-loops below the plane of the bar adapted to extend inwardly in overhanging spaced relation to the upper edge of said holder neck.

10. A bar traveler for a spinning ring, comprising a thread-engaging bar having depending

legs terminating in bearing arms, said bar being bent laterally into substantially the shape of a V and being provided at its apex with an integrally formed thread-guiding loop pending therefrom and opening upwardly, said loop including a neck portion and a lower enlarged portion extending on opposite sides of the bar-apex and whose com-

ponent parts are in the corresponding vertical planes intersecting the V-portions of the thread-engaging bar, the loop being formed by inner and outer bends with the inner bends constituting guides for the thread.
